UNITED STATES PATENT OFFICE.

JOHN I. MULLEN, OF PITTSBURG, PENNSYLVANIA.

WATERPROOF STOCKING.

No. 858,665.

Specification of Letters Patent.

Patented July 2, 1907.

Application filed April 11, 1907. Serial No. 367,684.

To all whom it may concern:

Be it known that I, JOHN I. MULLEN, a citizen of the United States, residing at Pittsburg, in the county of Allegheny and State of Pennsylvania, have invented 5 certain new and useful Improvements in Waterproof Stockings, of which the following is a specification.

My invention relates to foot wear and particularly to hosiery and has for its object to provide a stocking which will be absolutely waterproof and which will at 10 the same time keep the feet warm.

My device is particularly adapted for use by surveyors, engineers and those similarly engaged whose duties necessitate walking in wet and rough places such as creeks, marshes and mines. For this class of work so 15 called waterproof shoes and rubber boots have been found to be unsuitable and unserviceable; the best so called waterproof shoes in use will more or less rapidly admit moisture and the rubber boots are both inconvenient and liable to puncture.

20 With my improved form of stocking any convenient make of shoe may be used and the feet kept perfectly dry and warm by the use of the novel stocking, thus insuring comfort and preventing colds and rheumatism.

Referring to the drawing forming a part of this specification, the figure represents a fragmentary view of a stocking made up in accordance with my invention.

In the illustration, 1 represents an elastic and absorbent fabric inner stocking, preferably of cotton.

2 represents a very thin waterproof stocking corresponding in shape to the inner stocking and preferably

made of gossamer rubber. 3 represents an outer stocking of heavier fabric, preferably of wool, to provide warmth and at the same time afford a cushioning effect between the shoe and the waterproof stocking to prevent wear and puncture of said intermediate rubber 35 covering.

I am aware that it is old in the art to associate cotton, woolen and similar fabrics with rubber in the manufacture of gloves and boots, and I expressly disclaim the broad use of these three materials, my invention consisting in the co-operation of the three to produce the 40 unitary result described.

Having thus fully described my invention I claim as novel and desire to protect by Letters Patent:

1. In a waterproof stocking, the combination of an inner absorbent fabric unit, an intermediate waterproof unit, and an outer cushioning fabric unit, substantially as described and for the purposes set forth. 45
2. A waterproof stocking comprising an inner cotton unit, an elastic rubber intermediate unit, and a thick 50 outer woolen unit, substantially as described and for the purposes set forth.
3. In an article of the class described, the combination of an inner absorbent fabric stocking, an elastic rubber stocking surrounding said inner stocking but unattached 55 thereto, and a cushioning unit surrounding the foot of said rubber stocking, for the purpose set forth.

In testimony whereof I have affixed my signature in presence of two witnesses.

JOHN I. MULLEN.
